Attorney

UNITED STATES PATENT OFFICE.

JOHN CLAY CALDWELL, OF MIAMI, FLORIDA.

SCISSORS.

Application filed June 14, 1923. Serial No. 645,457.

This invention relates to cutting instruments of the scissor or shear type and the primary object of the invention is to provide a pair of scissors or like cutting instrument embodying novel means for mounting the cutting blades, so as to prevent wear thereon, and to permit the ready adjustment thereof relative to one another.

Another prime object of the present invention is the provision of novel independent bearings for each cutting blade, and novel means for permitting the separation of the cutting blades after the cutting operation, so as to preclude undue wear on the blades and to permit the convenient operation thereof.

A further prime object of the invention is the provision of a novel compensating screw for the blades of the scissors and novel means for maintaining the independent bearings of the blades in proper alignment relative to one another.

A still further object of the present invention is to provide an improved pair of scissors or like cutting instrument of the above character, which will be durable and efficient in use, one that will be simple and easy to manufacture and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings:

Figure 1 is a side elevation of the improved pair of cutting scissors constructed in accordance with this invention.

Figure 2 is a transverse section through the pivot point of the scissors.

Figure 3 is a fragmentary side elevation of the improved scissors showing the blades thereof in their fully opened position.

Figure 4 is a detail perspective view of one of the bearings or compensating screw.

Figure 5 is a detail perspective view of one of the clamping screws.

Figure 6 is a detail transverse section through the cutting blades illustrating the position of the blades after the cutting stroke, and

Figure 7 is a detail transverse section through the blades of the scissors illustrating the position of the blades relative to one another during the cutting stroke.

Referring to the drawings in detail,

wherein similar reference characters designate corresponding parts throughout the several views, the letter A generally indicates the improved pair of scissors, which embody the cutting blades 10 and 11 and the manipulating handles 12 and 13 therefor. At a point intermediate the blades 10 and 11 and the handles 12 and 13, the blades 10 and 11 are increased in width to provide enlarged portions 14 for permitting the ready connection of the blades together.

As clearly shown in Figure 6 of the drawings the blades 10 and 11 are normally arranged at an angle to the handles which insures the proper positioning of the cutting edges 15 of the blades relative to one another during the cutting operation. By this construction, it can also be seen that as the blades move to their fully closed position, the same will be separated from one another, thus preventing undue wear thereon and permitting the easy operation thereof. The relative positions of the blades 10 and 11 during the cutting operation can be readily seen by referring to Figures 6 and 7 of the drawings.

In order to insure the easy manipulation of the blades I provide independent bearings for each blade and means for adjusting the blades relative to one another. The novel means for connecting the blades together and for mounting the blades comprises a screw 20 embodying a relatively large flat head 21 and a threaded shank 22. It can be seen that the screw 20 is of the machine type. This screw is adapted to be received in a retaining member 25 which forms an important feature of this invention. The retaining member 25 embodies an enlarged disk-shaped head 26, which is adapted to be received in a disk-shaped recess 27 formed in the inner face of the enlargement 14 of the blade 10. An axially disposed stud 27 is formed on the disk 26 and is provided with an axially disposed internally threaded socket 28 for receiving the shank 22 of the clamping screw 20. It is to be also noted at this point that the shank 22 adjacent to the head 21 of the screw 20 is left plain so as to form a bearing for the blade 10. The outer surface of the stud 27 is provided with male threads 29 and the stud is threaded into an internally threaded axially disposed recess 30 formed in the enlargement 14 on the cutting blade 11. The extreme outer end of the shank 27 is

provided with a screw driver receiving slot 30, which permits the easy holding of the retaining member 25 against movement during the adjusting of the clamping screw 20.

5 It can be seen that the plate 26 is first placed into the recess 27, after which the screw 20 is threaded into the socket 28 formed in retaining member 25 and this construction provides a bearing for the blade 10. Now the blade 11 is placed on and threaded, which forms a bearing therefor and permits the adjusting of the blade 11 in 10 relation to the blade 10, thereby forming a compensating device, which is readily ap-
15 parent to those skilled in the art.

From the foregoing description, it can be seen that I have provided an improved cutting instrument of exceptionally durable and simple construction, which will be easy 20 to manipulate and which will entirely eliminate undue wear upon the cutting blades thereof.

Changes in details may be made without departing from the spirit or the scope of this invention.

25

What I claim as new is:

In a cutting device, a pair of companion cutting blades, handles formed on the rear ends of the blades, means pivotally connecting the blades together comprising a clamp- 30 ing screw having a bearing portion arranged to extend through one blade, the last mentioned blade having a disk-shaped recess formed in its inner face, a retaining member including a threaded shank, a disk-shaped 35 plate, the plate being adapted to be fitted in the recess of the last mentioned blade, the other blade having a threaded opening formed therein for receiving the shank of the retaining member, the shank of the re- 40 taining member having a threaded socket to receive the shank of the clamping screw.

In testimony whereof I affix my signature.

JOHN CLAY CALDWELL.
